United States Patent Office

Des. 193,997
Patented Nov. 6, 1962

193,997

ANIMATED TOY FIGURE

George Kolberg, 184 5th Ave., New York, N.Y.

Filed Dec. 12, 1961, Ser. No. 67,888

Term of patent 3½ years

(Cl. D34—15)

Fig. 1

Fig. 2

Fig. 3

FIG. 1 is a front elevational view of an animated toy figure, showing my new design;

FIG. 2 is a side elevational view thereof;

FIG. 3 is a top plan view thereof;

FIG. 4 is a rear view on a smaller scale.

I claim:

The ornamental design for an animated toy figure, as shown.
